Attorney

UNITED STATES PATENT OFFICE.

MARY E. HARRIS, OF SAN FRANCISCO, CALIFORNIA.

DESIGN FOR A STATUETTE OR DOLL.

51,415.

Specification for Design.

Patented Oct. 23, 1917.

Application filed July 23, 1917. Serial No. 182,357. Term of patent 3½ years.

To all whom it may concern:

Be it known that I, MARY E. HARRIS, a citizen of the United States, residing at the city and county of San Francisco and State of California, have invented a new, original, and ornamental Design for Statuettes or Dolls, of which the following is a specification, reference being had to the accompanying drawing, forming part thereof.

The figure is a perspective view of a statuette or doll, showing my new design.

I claim:

The ornamental design for a statuette or doll, as shown.

MARY E. HARRIS.
